UNITED STATES PATENT OFFICE

2,099,821

POWER CLOCK OF SMALL DIAMETER

Thomas V. Moore, La Porte, and Winfield C. Landry, Houston, Tex., assignors to Standard Oil Development Company, a corporation of Delaware

Application November 20, 1934, Serial No. 753,814

2 Claims. (Cl. 185—40)

This invention relates to improvements in a power clock such as is used to turn the chart in an instrument.

In some instruments, especially those used to obtain data within a well, a clock is used to turn the chart upon which the data is recorded. In the ordinary type of clock, the arrangement of the mechanism is such that a large case is required to use a clock with sufficient power to turn the chart.

It is an object of this invention to construct a clock which can be fitted into a relatively small case in order that the instrument with which the clock is used may be run in wells equipped with small tubing.

It is a further object of this invention to so improve the mechanism of such a clock as to enable it to be constructed of relatively small diameter without sacrificing the power of the clock or the ruggedness of its construction.

Other objects will be apparent from the specification and from the accompanying drawing in which latter—

Fig. 1 is a longitudinal sectional view showing a preferred form of apparatus for carrying out the invention;

Fig. 2 is a longitudinal sectional view taken at right angles to the showing in Fig. 1, and

Fig. 3 is a transverse sectional view taken along the line III—III of Fig. 1.

Referring particularly to the drawing, reference numeral 1 designates a housing for the clock device. The housing 1 is an elongated cylinder of greater length than the previously used clock housings. The housing 1 encloses a clock mechanism for driving a drive shaft 3 at a predetermined rate of speed. The drive shaft 3 has driving connection with an article to be driven in rotation such as a cylindrical supporting drum 5 for the chart 6 of a recording instrument. The shaft 3 is driven in rotation by means of a main spring 8 which is secured to the drive shaft 3 and is coiled in a plane perpendicular to the longitudinal axis of the housing 1. The main spring 8 is disposed in an end wall 9 of the housing 1.

The speed of rotation of the drive shaft 3 is controlled through the following arrangement of parts: A balance wheel 12 is mounted for rotation upon a shaft 13 which extends perpendicularly to the longitudinal axis of the housing 1 and is supported by the side walls of the housing 1. The balance wheel 12 is operatively connected to an escapement stop rod 15. The escapement stop rod is operatively connected with an escapement wheel 18 which is mounted for rotation upon a shaft 19 which extends perpendicularly to the longitudinal axis of the housing 1 and is

supported by the side walls of the housing 1. The shaft 19 carries a gear 20 which meshes with a gear 21 mounted upon a shaft 23 which extends perpendicularly to the longitudinal axis of the housing 1. The shaft 23 carries a gear 24 which meshes with a gear 25 mounted upon a shaft 26. The shaft 26 extends perpendicularly to the longitudinal axis of the housing and carries a gear 27 which meshes with a gear 30 mounted upon a shaft 31. The shaft 31 extends perpendicularly to the longitudinal axis of the housing 1. The shaft 31 is provided with a bevel gear 32 which with a bevel gear 33 carried by the drive shaft 3. The shafts 13, 19, 26 and 31 are all disposed in alignment along the longitudinal axis of the housing 1.

By means of the bevel gears 32 and 33, the drive shaft 3 is connected to the first shaft 31 of the train of gears, each shaft of which is perpendicular to the longitudinal axis of the instrument, all of the shafts being in alignment longitudinally of the housing 1. As a result of this construction, the entire clock mechanism can be placed in a housing of relatively great length. The relatively small diameter of the housing 1 is obtained without sacrificing the power of the clock or the ruggedness of its construction.

Various changes may be made within the scope of the appended claims in which it is desired to claim all novelty inherent in the invention as broadly as the prior art permits.

We claim:

1. A clock-work mechanism for use in deep well instruments including a housing carrying rotatably a driving shaft, a main spring in the housing secured to the shaft coiled in a plane perpendicular to the longitudinal axis of the housing, a train of gears and pinions of varying sizes and an escapement operatively connected with the shaft, the shafts of the train of gears and escapement being disposed perpendicularly to the longitudinal axis of the housing and in a plane of the longitudinal axis of the housing, a balance wheel, and a pallet fork operatively connected to the escapement and balance wheel, the balance wheel and fork being mounted for oscillation on shafts parallel with the gear shafts whereby the internal diameter of the housing can be of a size only sufficiently larger than the diameter of the largest gear to permit of rotation of the train of gears.

2. A clock-work mechanism, according to the preceding claim, in which all of the gears are substantially the same size.

THOMAS V. MOORE.
WINFIELD C. LANDRY.
